United States Patent Office

Des. 176,050
Patented Nov. 8, 1955

176,050

AWNNG

Winters O. Wendel, Johnstown, Pa.

Application August 26, 1954, Serial No. 32,040

Term of patent 14 years

(Cl. D21—6)

The single figure is a perspective view of an awning showing my new design, with the full line disclosure being repeated throughout the awning as indicated by the broken lines, except for the broken line disclosure of the bracket.

I claim:

The ornamental design for an awning, substantially as shown and described.
